UNITED STATES PATENT OFFICE.

HENRY DUISEN, OF ST. LOUIS, MISSOURI.

PLUMB AND LEVEL.

SPECIFICATION forming part of Letters Patent No. 752,535, dated February 16, 1904.

Application filed June 27, 1903. Serial No. 163,434. (No model.)

To all whom it may concern:

Be it known that I, HENRY DUISEN, a citizen of the United States, residing at St. Louis, in the State of Missouri, have invented a new and 5 useful Plumb and Level, of which the following is a specification.

This invention is a combined plumb and level, the object being to provide an exceedingly cheap and simple device consisting of 10 few parts so constructed and arranged that the device is not likely to get out of order.

With this object in view the invention consists in the novel features of construction hereinafter fully described, and pointed out 15 in the claims.

In the drawings forming part of this specification, Figure 1 is a perspective view of a combined plumb and level constructed in accordance with my invention. Fig. 2 is a face 20 view of a portion of the stock, showing the pointer arranged in the recess, the glass and face-plate being removed. Fig. 3 is a transverse sectional view taken through the stock. Fig. 4 is a detail perspective view, partly in 25 section, showing a portion of the recess, stock, and the corner-blocks arranged therein. Fig. 5 is a detail perspective view of the pointer. Fig. 6 is a detail perspective view of the circular plate carrying the arbor upon which the 30 pointer turns. Fig. 7 is a detail view of said arbor. Fig. 8 is a detail perspective view of the face-plate. Fig. 9 is a view of the glass held in place by the face-plate.

In carrying out my invention I employ a 35 stock A, which is substantially similar to the stock of an ordinary level. In the face of this stock is produced a square recess A', and fitting in the corners of the recess are the blocks B, cut away, as shown at B', so that when the 40 blocks are arranged in four corners of the recess a substantially circular subrecess will be provided, spaces C being left free between the ends of the corner-blocks. A circular plate D is adapted to fit in the circular subrecess, 45 said plate having a central threaded aperture D', and this plate is also provided with four angular extensions E, which fit into the spaces C, the outer ends of said angular extensions lying flush with the outer surface of the cor-

ner-blocks B. An arbor F is connected to the 50 circular plate D, said arbor having a threaded end F', which engages or screws into the threaded aperture D', and this arbor is also formed with a shoulder F². The pointer or indicator G has a central opening G', through 55 which the arbor passes, the outer end of said arbor being threaded, as shown at F³, and upon which the nut H is screwed. The pointer G is essentially triangular in shape, although it may be any shape desired so long as the upper end is pointed and the lower end heavier than the upper end, so as to maintain the pointer in a perpendicular position at all times.

I indicates a piece of glass which is adapted 65 to fit within the recess A', the corners of the glass being removed, so that the fastening-screws can be passed through the face-plate and corner-blocks into the stock, thereby avoiding the necessity of drilling holes in the 70 glass. K indicates the face-plate, having a circular opening K' and corner-openings K², through which the screws pass, and the corner-blocks B are also provided with apertures B², through which the fastening-screws pass. 75

It will thus be seen that all of the parts of my combined plumb and level are so constructed and arranged that the device is not at all likely to get out of order, and it is also obvious that the device will be accurate, as there is nothing whatever to interfere with its proper operation, as all dust and dirt are entirely excluded. The circular plate B may be graduated as desired; but in the drawings I have only shown four marks for the purpose of indicating perpendicular and horizontal positions. 80

Having thus fully described my invention, what I claim as new, and desire to secure by Letters Patent, is—

1. A device of the kind described comprising 90 a stock having a recess therein, corner-blocks arranged in said recess, a plate arranged also in the recess and provided with extensions resting between the corner-blocks, a pointer or indicator connected to the plate, 95 a glass and face-plate secured within the recess, substantially as described.

2. A combined plumb and level comprising

a stock having a square recess, corner-blocks secured in the recess, the circular plate arranged in the recess and provided with angular extensions resting between the corner-blocks, an arbor carried by the circular plate, a pointer arranged upon said arbor, the glass plate resting upon the corner-blocks, and the

face-plate for securing the said parts in place, substantially as set forth.

HENRY DUISEN.
